(57) **CLAIM**

The ornamental design for fluid connector, as shown and described.

DESCRIPTION

FIG. 1 is a top, front, right perspective view of a fluid connector showing my new design;

FIG. 2 is a bottom, rear, left side perspective view of the fluid connector shown in FIG. 1;

FIG. 3 is a front elevational view of the fluid connector shown in FIG. 1, to which the rear elevational view is identical;

FIG. 4 is a right side elevational view of the fluid connector shown in FIG. 1, to which the left side elevational view is identical;

FIG. 5 is a bottom plan view of the fluid connector shown in FIG. 1;

FIG. 6 is a top plan view of the fluid connector shown in FIG. 1;

FIG. 7 is a cross-sectional view of the fluid connector shown in FIG. 1, taken at line VII-VII in FIG. 6;

FIG. 8 is a cross-sectional view of the fluid connector shown in FIG. 1, taken at line VIII-VIII in FIG. 6; and,

FIG. 9 is a cross-sectional view of the fluid connector shown in FIG. 1, taken at line IX-IX in FIG. 5.
